UNITED STATES PATENT OFFICE.

PLESANT S. TORRENCE, OF SALISBURY, NORTH CAROLINA.

METAL SHINGLE.

Application filed March 12, 1923. Serial No. 624,633.

To all whom it may concern:

Be it known that I, PLESANT S. TORRENCE, a citizen of the United States, residing at Salisbury, in the county of Rowan 5 and State of North Carolina, have invented a new and useful Metal Shingle, of which the following is a specification.

This invention relates to metal shingles, and the object thereof is to provide leak preventing joints between adjacent shingles.

Another object is to provide shingles of this character equipped with a plurality of water breaks and troughs to avoid all possibility of water seeping through the joints.

With the foregoing and other objects in view which will appear as the description proceeds, the invention resides in the combination and arrangement of parts and in the details of construction hereinafter described 20 and claimed, it being understood that changes in the precise embodiment of the invention herein disclosed may be made within in the scope of what is claimed without departing from the spirit of the invention.

25 In the accompanying drawings:—

Figure 1 represents a transverse section taken on the line 1—1 of Fig. 2 showing the improved means for preventing leakage at the joint.

30 Fig. 2 is a top plan view of a portion of the plurality of shingles connected by this improved joint, and

Fig. 3 is a bottom plan view thereof.

In the embodiment illustrated, two sheet 35 metal shingles 1 are shown having their adjacent side edges connected by a joint 15. The shingle 1 has a nailing flange 2 and at the rear of this flange between it and the body portion of the shingle are two laterally spaced troughs 3 and 4 extending at obtuse angles to each other with a bead 5 formed at the vertex thereof to provide a water break. Another bead 6 is formed at the upper end of trough 3 by folding the 40 sheet metal longitudinally at this point the inner wall of said fold being in the form of a compound curve in cross section the bulged portion 6^a of which forms one member of a lock to be presently more fully described.

45 The trough 3 is designed to form a pocket to receive the edge 11 of an adjacent shingle, the mouth of said pocket being contracted and the outer face of the edge 11 being designed to contact with the bulge 6^a of bead 6, forming a tight joint. At the base of this 50 flange 11 is formed a bead 12 which fits up

over the bead or water break 7 located between the upper edge of the trough 4 and the nailing flange 2 forming a water tight joint at this point. The break 7 is considerably higher than break 5 so that all danger of the water overflowing break 7 is prevented. By this arrangement when the flange 11 is inserted in the pocket 3 its edge terminates short of the bottom of the pocket and 55 its outer face bears against the inner face of the bead bulge 6^a forming a substantially water-tight joint, but should any water leak past this joint and enter the pocket 3, it will flow down through said trough-like pocket 60 and be discharged onto the next shingle below. Should a sufficient amount of water enter the pocket 3 to overflow, it will enter the trough 4 which is sufficiently large and 65 deep to conduct the water without obstruction and discharge it onto the shingle below preventing all possibility of the water passing the bead 7 and seeping through onto the roof below.

From the above description it will be seen 70 that a joint constructed as herein shown and described will prevent all possibility of leakage and will freely carry off any water which may enter it.

Various changes in the form, shape, proportion and other minor details of construction may be made without departing from the spirit or sacrificing any of the advantages of the claimed invention.

75 I claim:—

1. The combination of two adjacent shingles one having a nailing flange and a plurality of longitudinally extending troughs with a water break between them and one at the outer edge of the outer trough, the outer break being higher than the inner, the other shingle closely contacting with the nailing flange and the outer water break of the first mentioned shingle and having a flange to enter one of said troughs and interlocking engage the outer wall thereof, said wall having a bulge near its outer edge to engage said flange and form a tight joint between them, the edge of said flange terminating short of the bottom of the trough. 100

2. A joint for metal shingles comprising a shingle having a nailing flange and a pair of oppositely extending obliquely disposed troughs with beads at the outer upper edges thereof and one between them, the intermediate bead being lower than the others, and another shingle having a flange adapt- 110

ed to enter one of said troughs to form a closure therefor, said last mentioned shingle overlying and tightly fitting the nailing flange of the trough carrying shingle and having a hollow bead at the base of its flange to tightly fit over the outermost water break of the first mentioned shingle.

3. The combination of a pair of metal shingles, one having a nailing flange along 10 its side edge, and provided in rear of said flange with a pair of longitudinally extending troughs with a water break arranged between them, said troughs having overhanging loop-like beads at their outer edges forming 15 a locking member and a water break respec-

tively, said beads being of a height greater than said intermediate water break; the other shingle having a flange to enter one of said troughs and interlockingly engage said locking member, said flange having an outward 20 bulge to fit over and tightly engage the outer water break and the nailing flange of the other shingle.

In testimony that I claim the foregoing as my own, I have hereto affixed my signature 25 in the presence of two witnesses.

PLESANT S. TORRENCE.
